UNITED STATES PATENT OFFICE

WILLIAM E. LEIBING, OF SAUSALITO, CALIFORNIA, ASSIGNOR TO LYONS-MAGNUS, INCORPORATED, OF SAN FRANCISCO, CALIFORNIA, A CORPORATION OF DELAWARE

DESIGN FOR A SIRUP OR BEVERAGE DISPENSER

Application filed January 19, 1931. Serial No. 38,350. Term of patent 7 years.

To all whom it may concern:

Be it known that I, WILLIAM E. LEIBING, a citizen of the United States, residing at Sausalito, in the county of Marin and State of California, have invented a new, original, and ornamental Design for Sirup or Beverage Dispenser, of which the following is a specification, reference being had to the accompanying drawing, forming a part thereof.

I claim:

The ornamental design for a sirup or beverage dispenser, as shown.

WILLIAM E. LEIBING.
